UNITED STATES PATENT OFFICE.

DAVID B. WHISTLER, OF DAYTON, OHIO, ASSIGNOR TO THE RECORDING AND COMPUTING MACHINES COMPANY, OF DAYTON, OHIO, A CORPORATION OF OHIO.

FARE-INDICATOR.

1,100,041.

Specification of Letters Patent. Patented June 16, 1914.

Application filed November 16, 1912. Serial No. 731,715.

To all whom it may concern:

Be it known that I, DAVID B. WHISTLER, a citizen of the United States, residing at Dayton, in the county of Montgomery and 5 State of Ohio, have invented certain new and useful Improvements in Fare-Indicators, of which the following is a specification, reference being had therein to the accompanying drawing.

10 This invention relates to fare indicators and the object of the invention is to provide an indicator which will exhibit indications of as many classes of fares as may be desired; which will exhibit these indications on both sides of the indicator; and 15 which will be of a very simple construction having but a small number of parts and having these parts of such a character and so arranged that they are not liable to be 20 come disarranged or to be rendered inoperative.

A further object of the invention is to construct the indicator that it can be mounted at a point more or less remote from the 25 fare register and controlled in unison therewith.

A further object of the invention is to connect such an indicator with the setting and operating devices of a fare register in 30 such a manner that the operation of the former will cause one of the indications to be moved into indicating position and the operation of the latter will cause that indication to be exhibited; and further, to so 35 arrange the parts that the indication of the fare last registered will remain on exhibition until the setting mechanism has been actuated and will then be concealed from view.

40 In the accompanying drawings, Figure 1 is a vertical section taken longitudinally of the indicator and showing the mechanism thereof in front elevation; Fig. 2 is a transverse sectional view taken on the line 2—2 of Fig. 1 and looking in the direction of the arrows; Fig. 3 is a section taken on the line 3—3 of Fig. 1 showing in detail the mechanism whereby the shutters are controlled by the shutting device; Fig. 4 is a 45 section taken on the line 4—4 of Fig. 1 showing the controlling device for the shutters in plan view; and Fig. 5 is a section taken on the line 5—5 of Fig. 1 showing in elevation the connection between the setting 50 device and the indicator.

In these drawings I have illustrated one embodiment of my invention and have shown the same in combination with the setting and operating devices of a fare register or recorder. The register itself is not 60 shown as it forms no part of the invention. In the present embodiment of the invention the setting device for the register comprises a vertical shaft 6 having rotary movement and the operating device comprises a vertical shaft or rod 7 having a reciprocatory movement. The arrangement of these devices, their connection with the register and the manner of operating the same is, of course, optional but, as here shown, are substantially the same as those shown and described in the application filed by Wilfred I. Ohmer and John E. McAllister for indicators on July 25th, 1912, Serial No. 711,431. 70 The indicator itself may be any one of various types but as here shown comprises a rotary drum having a series of indications arranged about its periphery and adapted to be selectively exhibited to the view of the passengers. It is desirable that the particular fare indication corresponding to the fare which has been registered should be exhibited on both sides of the indicator. While this could be accomplished by providing a drum large enough to carry two 80 series of indications on its periphery I prefer to provide two smaller drums each carrying one series of indications, the two drums being so connected that they will simultaneously exhibit the same indication. 90

In the present embodiment of the invention I have shown the indicator as comprising a casing 8 consisting of a lower portion 9 and provided on its opposite sides with sight openings 10 and adapted to contain a counting indicator 11 similar to that shown and described in the application above mentioned. Inasmuch as this counting indicator forms no part of the present invention it is sufficient to say that it is of 95 such a character that it will count and indicate on both sides of the indicator each fare received and will show at a glance the total number of fares received since the beginning of the run. The indicator casing also comprises an upper portion 12, preferably having its sides parallel but spaced apart a distance less than the distance between the sides of the lower portion of the casing. 100 Journaled at one end in the adjacent end 110

wall of the upper part of the casing and at the other end in a frame member 25 are two shafts 13 and 14 upon which are mounted indicator drums 15 and 16, respectively. 5 These drums are here shown as square in cross section and thus provided with four faces each of which carries a separate fare indication, such, for example, as the 3¢ and 5¢ cash fares, the pass and the ticket. The 10 side walls of this upper portion of the casing are each provided with sight openings 17 and 18 arranged in the opposite side walls, respectively, and in alinement with the respective indicator drums, thus causing the 15 one sight opening to be arranged some distance above the other. The two shafts 13 and 14 have secured thereto at one end gears 19 and 20 which are connected one with the other by means of an intermediate gear 21 20 mounted between the same. By means of this connection the two drums are caused to rotate simultaneously in the same direction and at the same speed. By having the fare indications arranged on the two drums in 25 the same order and setting one drum a half revolution in advance of the other it will be obvious that the same fare indication will be exhibited simultaneously at both sight openings. The setting of the drums to cause 30 them to exhibit the desired fare indication is preferably accomplished through the setting mechanism for the fare register and, to this end, the setting device or shaft, as well as the operating shaft for the register, are extended through the casing 8 at one end of 35 the indicating devices and the setting shaft has secured thereto a bevel gear 22 which meshes with a corresponding gear 23 carried by a stud 24 mounted on the vertical frame member 25 which carries one end of each of 40 the shafts 13 and 14. Rigidly secured to the bevel gear 22 is a segmental gear 26 which meshes with a gear 27 on that end of the shaft 14, of the lower indicator drum, opposite the gear 20. Obviously, therefore, the 45 rotation of the setting shaft will cause the rotation of the two indicator drums and the gearing is of such a ratio that this rotation will cause each drum to move into exhibiting 50 a position that fare indication corresponding with the fare which the register has been set to register.

It is desirable that the fare indicated by the indicator should correspond always with 55 the last fare registered by the fare register. I have, therefore, provided means for concealing the fare indications from view until the register has been operated to register the fare which the indicator is set to indicate, exhibiting 60 the indication to view simultaneously with the operation of the operating mechanism of the register and again concealing the same when the setting mechanism is actuated to change the indication. Thus, when any indication is exhibited to view this indication

must necessarily correspond with the last fare previously registered. To accomplish this I provide two shutters or "flashes" which are indicated at 28 and 29, respectively, and, in the present instance, are in 70 the form of curved plates carried by arms 30 and 31 mounted on the shafts 13 and 14, respectively, there being preferably one arm at each end of each drum and the curved plates or flashes 28 and 29 being of a length 75 slightly greater than the length of the drum. These flashes are of such a width that when moved into position between the indicator drums and the respective sight openings they will entirely conceal the drums from 80 view.

The two flashes are so connected one to the other that they will move simultaneously in opposite directions, thus causing each flash to be moved into or out of alinement with its sight opening simultaneously with the corresponding movement of the other flash. This connection is made, in the present instance, by providing the upper flash 28 with a crank arm 32 which is connected by means 85 of a link 33 with an arm 32^a secured to the lower flash 29. Consequently, when movement is imparted to one flash the other flash must move therewith. Preferably, a link and crank arm 32 are provided at each end 90 of the indicator drums, thus preventing any tendency to twist or bind on the part of the flashes. A spring 34 is connected with the flashes and tends to move the same into a position between the sight openings and the 95 respective drums. This spring is preferably connected with an arm 35 mounted on the outer side of the frame member 25 and connected with one of the arms 30 of the upper flash. In the present arrangement of 100 the mechanism the upper drum is loosely mounted on its shaft and the arms carrying the flash are rigidly secured to this shaft. Consequently, the arm 35 is connected with the flash by rigidly securing it to the outer 105 end of the shaft 13. This arm 35 is actuated by the movement of the operating shaft to move the flashes against the tension of the spring 34 and exhibit the indications to 110 view. To this end I have provided the arm 115 35 with a laterally extending projection or pin 36 arranged in the path of a finger 37 rigidly secured to the operating shaft 7. Thus, when the operating shaft is reciprocated to operate the register the finger 37 120 will engage the pin on the arm 35 and move the flashes upward out of alinement with the respective sight openings. A suitable catch is provided to then retain the flashes 125 in their elevated positions and allow the fare indication to remain on exhibition. This catch is here shown as comprising an arm 38 connected with the flash, preferably by connecting it with the arm 35. The arm 38 has one edge cut away to form a shoulder 130

39 adapted to engage one end of a finger 40 pivotally mounted at 41 on the frame member 25. A spring 42 connected at one end with the finger 40 and at the other end with the frame member 25 tends to move the finger 40 downward into alinement with the shoulder of the finger 38 and to hold the same in this position until sufficient force is applied thereto to overcome the tension of 10 the spring.

It will be apparent that when the operating device has moved the arms 35 and 38 upward a distance sufficient to carry the flashes out of alinement with their sight 15 openings the shoulder 39 will be carried past the end of the finger 40 and this finger will be moved by its spring into alinement with the shoulder of the arm 38, thus locking the arm and the flashes in their inoperative positions. The flashes are preferably released 20 by the action of the setting device to permit the spring 34 to move the same into their operative positions at the first movement of the setting device to change the indication. While this may be accomplished 25 in various ways I have shown a second finger 43 mounted on the axis of the finger 40 and rigidly connected with said finger. This second finger 43 has a nose 44 adapted to engage 30 a toothed segment 45 rigidly secured to the setting shaft 6 and to ride over the teeth of said segment when the setting shaft is rocked about its axis. The spring 42 of the finger 40 tends to hold the nose of the 35 finger 43 in engagement with the toothed segment. The movement imparted to the finger 43 as its nose rides over one of the teeth of the segment 45 is sufficient to carry the finger 40 out of engagement with the 40 shoulder of the arm 38 and thus release the flashes and permit the spring 34 to move them into their operative positions, that is, in the positions in which they will conceal the fare indications from view. The flashes 45 remain in this position until the operating device is again actuated to register another fare when the operation above set forth is repeated.

It will be apparent from the foregoing 50 description that I have provided an indicator which may be mounted separately and at a point remote from the fare register and which will indicate only the last fare previously registered, thus preventing the manipulation of the mechanism to permit a fare to be registered and then the indication 55 quickly changed to indicate another fare. Further, it will be apparent that the mechanism by means of which this is accomplished 60 is very simple in construction and positive in its operation.

While I have shown and described one 65 embodiment of my invention it will be understood that this has been chosen for the purposes of illustration only and that I do

not desire to be limited to the details of construction shown and described, for obvious modifications will occur to a person skilled in the art.

Having thus fully described my invention, what I claim as new and desire to secure by Letters Patent, is:—

1. The combination, with setting and operating devices mounted independently of and adapted, respectively, for connection with the setting and actuating mechanisms of a fare register, and an indicator separate from said fare register and adapted to exhibit any one of a plurality of fare indications, of a connection between said indicator and said setting device to move one of said fare indications into indicating position, means controlled by said setting device to conceal said indications from view, and a connection between said concealing means and said operating device to cause said indication to be exhibited when said operating device is actuated.

2. The combination, with setting and operating devices mounted independently of and adapted, respectively, for connection with the setting and actuating mechanisms of a fare register, and an indicator separate from said fare register and adapted to exhibit any one of a plurality of fare indications, of means controlled by said setting device to move one of said indications into indicating position and to conceal the indication, and means controlled by said operating device to exhibit said indication.

3. The combination, with setting and operating devices mounted independently of and adapted, respectively, for connection with the setting and actuating mechanisms of a fare register, and an indicator separate from said fare register and adapted to exhibit any one of a plurality of fare indications, of means controlled by said setting device to move one of said indications into indicating position, means controlled by said operating device to exhibit said indication, and means controlled by the further movement of said setting device to conceal from view any indication in indicating position.

4. The combination, with setting and operating devices mounted independently of and adapted, respectively, for connection with the setting and actuating mechanisms of a fare register, and an indicator separate from said fare register and mounted adjacent to said setting and operating devices, said indicator comprising a drum having thereon a plurality of fare indications, and a casing inclosing said drum and having a sight opening, of a connection between said indicator drum and said setting device to move said drum to bring any one of said indications into alinement with said sight opening, a flash mounted to be moved into

and out of a position between said drum and said sight opening, and means controlled by said operating device to move said flash out of said position.

5. The combination, with setting and operating devices mounted independently of and adapted, respectively, for connection with the setting and actuating mechanisms of a fare register, and an indicator separate from said fare register and mounted adjacent to said setting and operating devices, said indicator comprising a drum having thereon a plurality of fare indications, and a casing inclosing said drum and having a sight opening, of a connection between said indicator drum and said setting device to move said drum to bring any one of said indications into alinement with said sight opening, a flash mounted to be moved into and out of a position between said drum and said sight opening, means controlled by said operating device to move said flash out of said position, and a detent to retain said flash out of said position independently of the further movement of said operating device.

6. The combination, with setting and operating devices mounted independently of and adapted, respectively, for connection with the setting and actuating mechanisms of a fare register, and an indicator separate from said fare register and mounted adjacent to said setting and operating devices, said indicator comprising a drum having thereon a plurality of fare indications, and a casing inclosing said drum and having a sight opening, of a connection between said indicator drum and said setting device to move said drum to bring any one of said indications into alinement with said sight opening, a flash mounted to be moved into and out of a position between said drum and said sight opening, means controlled by said operating device to move said flash out of said position, a detent to retain said flash out of said position independently of the further movement of said operating device, and means controlled by the further movement of said setting device to actuate said detent to release said flash and permit the same to return to its position between said drum and said sight opening.

7. The combination, with a rotary setting device and a reciprocatory operating device mounted independently of and adapted, respectively, for connection with the setting and actuating mechanism of a fare register, and an indicator separate from said fare register and mounted adjacent to said setting and operating devices, said indicator comprising a drum having a plurality of fare indications, and a casing for said drum having a sight opening, of a connection between said drum and said rotary setting means to control the position of said drum,

a flash movably mounted adjacent to said drum, a spring tending to move said flash into a position between said drum and said sight opening, a projection carried by said operating member, and an arm secured to said flash and having a part arranged in the path of said projection, whereby the reciprocation of said operating member will move said flash against the tension of said spring.

8. The combination, with a rotary setting device and a reciprocatory operating device mounted independently of and adapted, respectively, for connection with the setting and actuating mechanisms of a fare register, an indicator separate from said fare register and mounted adjacent to said setting and operating devices, said indicator comprising a drum having a plurality of fare indications, and a casing for said drum having a sight opening, of a connection between said drum and said rotary setting means to control the position of said drum, a flash movably mounted adjacent to said drum, a spring tending to move said flash into a position between said drum and said sight opening, a projection carried by said operating member, an arm secured to said flash and having a part arranged in the path of said projection, whereby the reciprocation of said operating member will move said flash against the tension of said spring, a second arm secured to said flash, a spring-pressed detent adapted to engage said second arm to hold said flash out of its position between said drum and said sight opening, and means actuated by said setting device to move said detent into an inoperative position.

9. The combination, with a rotary setting device and a reciprocatory operating device mounted independently of and adapted, respectively, for connection with the setting and actuating mechanisms of a fare register, an indicator separate from said fare register and mounted adjacent to said setting and operating devices, said indicator comprising a drum having a plurality of fare indications, and a casing for said drum having a sight opening, of a connection between said drum and said rotary setting means to control the position of said drum, a flash movably mounted adjacent to said drum, a spring tending to move said flash into a position between said drum and said sight opening, a projection carried by said operating member, an arm secured to said flash and having a part arranged in the path of said projection, whereby the reciprocation of said operating member will move said flash against the tension of said spring, a second arm secured to said flash, a spring-pressed detent adapted to engage said second arm to hold said flash out of its position between said drum and said sight opening, a finger connected to said detent and

having a nose, and a toothed segment connected with said rotary setting device and arranged to engage the nose of said finger, when said setting device is rotated, to move 5 said detent into an inoperative position.

10. The combination, with a setting device for a fare register, a fare indicator comprising a casing having a sight opening in each of two sides thereof, said openings 10 being arranged at different heights, two indicator drums mounted within said casing and arranged in alinement with the respective sight openings, a connection between said drums to cause the same to move in unison, said drums being arranged to simultaneously exhibit the same fare indication 15 at the respective sight openings, and an operative connection between one of said drums and said setting device.

20 11. The combination, with a setting device for a fare register, a fare indicator comprising a casing having a sight opening in each of two sides thereof, said openings being arranged at different heights, two indicator drums mounted within said casing and arranged in alinement with the respective sight openings, a connection between said drums to cause the same to move in unison, said drums being arranged to simultaneously exhibit the same fare indication 25 at the respective sight openings, an operative connection between one of said drums and said setting device, a flash for each drum adapted to be moved between its drum and the corresponding sight opening, connections 30 between said flashes to cause the same to move in unison, and means tending to move said flashes into positions between their drums and the respective sight openings.

40 12. The combination, with a setting device for a fare register, a fare indicator comprising a casing having a sight opening in each of two sides thereof, said openings 45 being arranged at different heights, two in-

dicator drums mounted within said casing and arranged in alinement with the respective sight openings, a connection between said drums to cause the same to move in unison, said drums being arranged to simultaneously exhibit the same fare indication 50 at the respective sight openings, an operative connection between one of said drums and said setting device, a flash for each drum adapted to be moved between its drum and the corresponding sight opening, connections 55 between said flashes to cause the same to move in unison, means tending to move said flashes into positions between their drums and the respective sight openings, a 60 detent to hold said flashes out of said positions, and means controlled by said setting device to release said detent.

13. The combination, with a setting device for a fare register, a fare indicator 65 comprising a casing having a sight opening in each of two sides thereof, said openings being arranged at different heights, two indicator drums mounted within said casing and arranged in alinement with the respective sight openings, a connection between 70 said drums to cause the same to move in unison, a connection between one of said drums and said setting device to impart rotary movement to said drums, a flash for each 75 drum, a spring tending to move each flash into a position between its drum and a corresponding sight opening, means actuated by said operating device to move said flashes out of said positions, means to retain said 80 flashes out of said positions, and means controlled by said setting device to release said retaining means.

In testimony whereof, I affix my signature in presence of two witnesses.

DAVID B. WHISTLER.
